A. S. HUGHES.
STEEL PARTITION AND DOOR.
APPLICATION FILED SEPT. 16, 1919.

1,373,074.

Patented Mar. 29, 1921.

UNITED STATES PATENT OFFICE.

ARTHUR SHERIDAN HUGHES, OF MANSFIELD, OHIO.

STEEL PARTITION AND DOOR.

1,373,074.

Specification of Letters Patent.

Patented Mar. 29, 1921.

Application filed September 16, 1919. Serial No. 324,239.

To all whom it may concern:

Be it known that I, ARTHUR S. HUGHES, a citizen of the United States, residing at Mansfield, in the county of Mansfield and State of Ohio, have invented a new and useful Steel Partition and Door, of which the following is a specification.

This invention relates to a means for locking the panels of pressed steel partitions, 10 hollow doors and the like.

It is the primary object of this invention to provide a lock which will adapt itself to the varying thicknesses and irregularities of pressed steel sheets and yet will be strong 15 and secure.

Another object is to provide an interlocking construction which will hold panels without the necessity of spot welding and the consequent liability of buckling.

20 A further object is to construct a lock which will be practical from the shop standpoint and from that of economy.

The present invention is an improvement related to the construction described in my 25 pending application Serial No. 317,746, filed August 15, 1919.

In order to comprehend the scope and advantages of this invention, reference should be made to the drawing accompanying this 30 specification and forming a part thereof.

In the drawing:—

Figure 1 is a cross-sectional view of a part of a partition or door constructed in accordance with the invention.

35 Fig. 2 is a section taken on the line 2—2 of Fig. 1;

Fig. 3 is a section on the line 3—3 of Fig. 1;

Fig. 4 is a perspective detail view of a portion of a panel; and

Fig. 5 is another cross sectional view, but on a different plane from Fig. 1 and omitting the locking clip.

The numeral 10 designates a hollow stile 45 of a steel partition or door, and 11 designates a panel clamping molding consisting of two like parts or jaws 12 turned into the stile and separated by a space wide enough to admit panels of average thickness. A panel 50 13 is fitted between the jaws 12 and is locked in place by means to be described.

Each jaw 12 has a series of spaced indentations forming projections 14 of oblong shape running longitudinally with the stile as Fig. 52 shows. The oblong projections on the flanges oppose each other as seen in Fig. 3,

with the concave faces presented to the panel. The panel on its part has a series of round indentations forming projections 15 near its edge and running longitudinally therewith. 60 The spacing of projections 15 is the same as the spacing of projections 14, but the round projections are pressed or formed alternately at opposite sides of the panel. The round projections lock with the oblong 65 indentations when the panel is in position, and since the oblong indentations have usually a length about equal to twice the diameter of a round projection, provision is made for inequalities of manufacture, a lengthwise 70 adjustment of the panel in the jaws being possible. The width of indentations 14 is approximately equal to the diameter of projections 15.

An additional locking means for the 75 panel and stile jaws is provided in the form of a spring clip 16, elliptical in cross-section, which is of the length of the panel and has a split portion 17. This split portion or slot permits the clip to be slipped over 80 the end of the panel and jaws and forced into such position that the edges of the split press against the jaws while the clip encloses the panel edge and the oblong projections of the jaws. The elliptical shape of 85 the clip brings the inner edge of the panel tight against the inner wall of the clip, thus locking the clip against movement in one direction, while the tension of the clip against the jaws adjoining the oblong projections locks the clip against movement in 90 the opposite direction. The resiliency of 95 the clip tends to make it resume a more narrowly elliptical form, with the result that the panel edge is pressed against, while at the same time the jaws are under considerable pressure.

The round projections of the panel engaging with alternate right and left oblong indentations provided in the jaws form 100 a locking means which is under constant pressure from the clip.

The above described construction is well adapted not only for partitions between compartments and for doors, but can be used 105 to advantage in making metallic furniture, in Pullman car construction, and wherever metallic sheets and panels must be locked to a frame.

It will be noted that the present invention 110 consists of but three parts, the stile, the panel and the clip. Each of these parts is

in one piece, and no bolts, rivets, screws or welding are employed. The clip not only forces the stile jaws together thus gripping the interposed panel, but also presses against the panel directly along its edge. The panel is held by the pressure of the jaws as well as by the interlocking connection with the jaws. This makes a very tight and strong joint, avoiding the buckling of the panel 10 which spot welding frequently brings about.

While the invention has been described in detail, it should be understood that the description is illustrative of the preferred embodiment of the invention and does not 15 absolutely limit the same. I desire to be limited only by the appended claims.

What is claimed is:—

1. In combination, a stile, jaws provided on the stile, said jaws having a series of 20 spaced indentations, a panel inserted between the jaws and extended at its edge beyond the same having a complementary series of spaced projections for locking with the first-named indentations, and a clip directly engaging the jaws and panel to additionally lock the same.

2. In combination, a stile, jaws provided on the stile, said jaws having a series of 30 spaced oblong indentations, a panel inserted between the jaws and extended at its edge beyond the same having a complementary series of spaced circular projections for locking with the first-named indentations, and a clip directly engaging both jaws and

the panel along the edge thereof to additionally lock the same. 35

3. In combination, a stile having interior spaced jaws, a series of spaced oblong indentations formed on each jaw opposite each other, providing similar shaped projections 40 on the opposite face, a panel inserted between the jaws, and extended at its edge beyond the same, a series of spaced round projections formed on the panel and interlocking with the oblong indentations, said 45 round indentations being formed alternately on opposite faces of the panel, and a clip directly engaging the jaws and contacting with the panel, the projections on the jaws holding the clip from movement in one direction and the contact of the clip with the edge of the panel preventing movement in the opposite direction.

4. A stile having spaced jaws with outward projections, a panel inserted between 55 the jaws and extended at its edge beyond the same, and a substantially elliptical-shaped clip having a split portion to receive the jaws with the panel therebetween, the walls of the split engaging with the jaws 60 at one side of the projections and holding the clip from outward movement, and the extended edge of the panel engaging the inside of the clip and preventing inward movement of the latter. 65

In testimony that I claim the foregoing as my own, I have hereto affixed my signature.

ARTHUR SHERIDAN HUGHES.
